UNITED STATES PATENT OFFICE.

ELERT A. HILL, OF LOS ANGELES, CALIFORNIA, ASSIGNOR TO STOP-BURGLAR LOCK COMPANY, OF LOS ANGELES, CALIFORNIA, A CORPORATION OF CALIFORNIA.

LOCK.

Application filed January 13, 1922. Serial No. 529,064.

To all whom it may concern:

Be it known that I, ELERT A. HILL, a citizen of the United States, residing at Los Angeles, in the county of Los Angeles and

5 State of California, have invented new and useful Improvements in Locks, of which the following is a specification.

This invention particularly pertains to a permutation lock of the rotary-tumbler type

10 in which the operation of a lock-bolt in unlocking the lock is dependent upon the proper positioning of a plurality of rotary locking tumblers. Locks of this character are disclosed in the following co-pending

15 applications for United States Letters Patent: Application filed February 14, 1922, Serial No. 536,581, which has resulted in Letters Patent No. 1,480,759, issued Jan. 15,

1924; application filed April 1, 1922, Ser. No. 548,770, which has resulted in Letters Patent No. 1,480,760, issued January 15, 1924; application filed October 7, 1922, Ser. No. 593,006; application filed October 10, 1922, Ser. No. 593,534; application filed Oc-

20 tober 13, 1922, Ser. No. 594,369; application filed October 3, 1922, Serial No. 592,127; application filed Sept. 27, 1922, Serial No. 590,978; application filed December 19, 1923, Ser. No. 681,642.

25 An object of this invention is to provide a keyless lock embodying a series of push-buttons and a locking mechanism controlled thereby in such manner that the operation of the lock must necessarily be effected by depressing each of the push-buttons a pre-determined number of times and whereby the lock may be operated by manual pressure and the sense of feel without necessitating use of the sense of sight.

30 A particular object of this invention is to provide a construction in a lock of the above character by which the disposing of a tumbler in an unlocking position can not be detected from the exterior of the lock as by

35 sound or sense of touch: whereby the proper positioning of the rotary tumblers can not be effected by persons not knowing the combination of the lock other than by chance, and rendering extremely difficult and remote

40 45 50 the possibility of discovering the unlocking combination,

Another object is to provide a simple means whereby the unlocking combination may be readily changed and set to operate at numerous combinations.

55 Another object is to provide means in a rotary tumbler lock for determining the starting position of the tumblers so as to enable the operator to dispose the tumblers in their unlocking position.

60 A further object is to provide an arrangement whereby the lock may be readily fitted to be operated as a latch from one side thereof and freely opened from that side when the tumblers are either in or out of 65 their locking position.

65 With the foregoing objects in view, together with such other objects and advantages as may subsequently appear, the invention resides in the parts, and the combination, construction and arrangement of parts, and their equivalents, hereinafter described and claimed and illustrated by way of example in the accompanying drawings, in which:

70 Fig. 1 is a view in vertical longitudinal section of the lock partly in elevation as seen on the line 1—1 of Fig. 2.

75 Fig. 2 is a view in elevation and transverse section as seen on the line 2—2 of Fig. 80 1 on a reduced scale.

80 Fig. 3 is a view in horizontal section as seen on line 3—3 of Figs. 1 and 2 on a reduced scale, showing the lock as applied to a door such as is employed in buildings.

85 Fig. 4 is a detail in side elevation of a door showing the manner of forming the lock receiving slot therein.

90 More specifically 5 indicates the lock casting which is here shown as comprising separable side plates 6 and 7 adapted to extend on opposite sides of a door 8; the plate 6 being formed with inturned end wall 9 and the plate 7 being formed with inturned end wall 10 to form the front wall 95 of the lock casing. The wall 9 is here shown as formed with a longitudinal channel 11 one side of which is formed by a flange 12, and the wall 10 is formed with the inturned end flange 13 adapted to extend

100 into the channel 11 into engagement with the flange 13 whereby the side plates 6 and

7 may be readily connected together in detachable engagement with each other. The plates 6 and 7 are formed with inturned flanges 14 and 15 spaced from the front flanges 9 and 10 and also spaced from the edges of the plates to form flanges 16 and 17 adapted to extend over the sides of the door 8 as shown in Fig. 3, the casing as here shown being adapted to be applied to the ordinary wooden door such as is employed in buildings, and mounted in the door by setting in a slot 18 formed in the edge of the door as shown in Fig. 4. A backing plate 19 is attached to the back wall of the slot by screws 20 or other suitable fastenings which plate is formed with a series of threaded openings to receive screws 21 and 22 which are passed through aligned openings in the walls 9—10 and flanges 14—15, which screws serve to fasten the lock casing in the door and being inserted through the front wall of the lock casing are concealed when the door is closed and yet permit ready removal and replacement of the lock casing when occasion requires.

Formed on the wall 10 and flange 15 are opposed guide sleeves 23 and 24 in which a slide-bar 25 is reciprocally mounted; the bar being inserted in the sleeves through an opening 26 formed in the flange 15 communicating with the interior of the sleeve 24. A helical or spiral spring 27 is arranged in the sleeve 23 to exert a pressure longitudinally of the bar tending to move the latter to a retracted position. The slide bar serves as an arbor for a series of rotary tumblers 28, 29 and 30, each of which comprises a bushing 31 mounted to revolve on the bar and a toothed annulus 32 carried by the bushing and adapted to be turned to various positions thereon, a spring plate 33 affixed to the bushing having a finger 34 engaging with a recess 35 on the annulus to hold the annulus and bushing against rotation relative to each other. The teeth on the annulus comprise ordinary ratchet teeth 36 and are here shown as ten in number and numbered in their order around the annulus to facilitate setting the lock to certain combinations as will presently be explained.

Each bushing is formed with a transverse channel 37 adjacent to and extending longitudinally of the bar, and mounted on the bar is a series of spring pressed catches 38, 39 and 40 arranged to extend forward of each tumbler when the bar is in an advanced position and adapted to enter the channels 37 when the tumblers are turned to dispose the channels in alignment with each other and with the catches whereby the bar may be permitted to move to a retracted position under action of the spring 27. Each catch is here shown as embodying a disk 41 arranged in and guided by a transverse recess 42 in the bar and carried on a flat faced stem

43 extending through an opening in the bottom wall of the recess and formed with a head 44 adapted to abut against the underside of the recess wall to limit outward movement of the catch. A spring 45 is wound around the stem 43 and bears between the bottom of the recess and the underside of the disk and acts to normally maintain the catch in its outermost position. Formed on the outer face of the disk is a tooth 46 having a shoulder on the end thereof adjacent the tumbler and having an inclined top face as is common in catches to adapt it to ride under the bushing when the bar is advanced in opposition to the spring 27 with the channel out of alignment with the catch. Each catch is designed to engage a tumbler when the bar is in its advanced position when the channels are out of alignment with the catches to hold the bar against movement under action of the spring 27.

Carried by the plate 7 is a series of brackets 48, 49 and 50, each of which extends along the side of a tumbler opposite the side thereof adjacent the latch and serves in cooperation with a catch to hold the tumbler against movement longitudinally of the bar.

Extending through the plate 7 and projecting beneath the tumblers is a series of reciprocal push-pins 51, 52 and 53 having their inner ends guided in the brackets, and mounted on each push-pin is a catch 54 adapted to be engaged with the teeth on the adjacent tumbler in such manner that as the push-pin is advanced in one direction the tumbler will be caused to turn the length of a tooth and on return movement of the push-pin the catch will ride over and engage with the adjacent tooth. A spring 55 is wound on each push-pin and bears between the bracket and a pin 56 on the push-pin and acts to normally maintain the push-pin in its forwardmost position. The pin 56 rides in a slot 57 in the bracket which construction serves as a means for holding the push-pin against turning and also serves to limit longitudinal movement of the push-pin in either direction.

For the purpose of holding the tumbler against retrograde movement a catch 58 is mounted on the plate 7 and positioned to engage the ratchet teeth on the tumbler as shown in Fig. 2; the latch being mounted on a stem 59 to the outer end of which is attached a block 60 adapted to slide in an opening 61 in the plate 7 which block constitutes an indicator for designating a starting position of the tumbler, as will be later described. A spring 62 acts on the catch 58 to normally hold the latter in an advanced position with the outer end of the block 60 located within the opening 61. On rotation of the tumbler the catch 58 is moved out-

wardly in passing over a ratchet tooth and the block 60 is advanced a short distance in the opening 61 and when the catch rides over the end of the ratchet tooth the block 60 moves back into the recess.

As a means for indicating when a certain ratchet tooth is engaged by the catch 54 on the push-pin, a projecting pin 63 is mounted on the tumbler in such position as to engage

- 10 the catch 58 and cause the latter to retract a greater distance than when acted on by a ratchet tooth so as to move the block 60 until its outer end will project beyond the front face of the plate 7. By this arrangement the operator may determine the position of the tumbler either by observing the movement of the block 60 or by placing the fingers over the opening 61 while operating the push-pin. The pin 63 is set in a recess 20 64 in the outer face of the ratchet teeth and a recess 64 is provided on each tooth. To facilitate setting the pin 63 and also adjusting the annulus relative to the pushing each tooth bears a number as indicated in Fig. 2.
- 25 Mounted in the lock casing and carried by the wall 10 and flange 15 is a latch bolt 65, the outer end of which projects beyond the wall 10 and is adapted to engage the recess 66 in the door casing. The end of the latch bolt having an inclined face 67 to permit it riding into engagement with the recess on closing the door as is common in latch bolt construction. A spring 68 bears against the inner end of the latch bolt to normally maintain the latter in its outermost or locking position.

Extending into the lock casing from one side thereof is a sleeve 69 carrying a pin 70 adapted on rotation of the sleeve to engage

- 40 a pin 71 projecting from the side of the latch bolt 65 whereby the latch bolt may be retracted from one side of the lock casing; the sleeve 69 being fitted with a knob 72 by which it may be manually rotated. Extending into the lock casing from the side opposite the sleeve 69 is a shaft 73 fitted with a knob 74 by which it may be manually rotated, the inner end of which shaft extends into the sleeve 69 and is turnable relative thereto. An annular channel 75 is formed adjacent the inner end of the shaft, into which a set screw 76 on the sleeve extends to hold the shaft and sleeve against longitudinal movement relative to each other and also hold the shaft 73 against being withdrawn. The shaft 73 extends laterally beneath the latch bolt 65 and carries a projection 77 at a point beneath the latch bolt. Pivoted at 78 on the latch bolt and projecting upwardly from a slot 79 in the latter is an arm 80, the upper end of which terminates adjacent an inclined face 81 formed on the under side of the slide bar 25 at the rear end thereof; a spring 82 attached to the latch bolt 65 and connected to the arm 80, exerts an

upward pull thereon and serving to hold its upper end against the slide bar. Formed on the arm 80 is a tooth 83 which is adapted on depression of the arm 80 to extend into the path of travel of the projection 77 on the shaft 73; the arm 80 being adapted to be depressed by action of the inclined face 81 thereon when the slide bar 25 is moved rearwardly under action of the spring 27.

Pivoted at 84 in the lock casing and extending between the slide bar 25 and latch bolt 65 is a lever 85, the lower end of which extends into a recess 86 in the latch bolt in such fashion that as the latch bolt moves longitudinally the lever 85 will be rocked on its pivot 84. The upper end of the lever 85 extends into an elongated slot 87 on the under side of the slide bar 25 and normally abuts against the rear end wall of the slot, as shown in Fig. 1, when the latch bolt is 85 in its advanced or locking position. The slot 87 is of such length that the end walls thereof will be spaced apart a sufficient distance to permit rearward movement of the slide bar under action of the spring 27 without engaging the lever 85.

Assuming the parts to be positioned as shown in Fig. 1, that is, with the latch bolt advanced and in its locking position, and the slide bar retracted in opposition to spring 27 and held against movement by either of the catches 38, 39 or 40 engaging a tumbler, the operation in unlocking the lock will be as follows:

The push-pins 51, 52 and 53 are each 100 pressed inwardly a sufficient number of times to bring the pin 63 into operative engagement with the latch 58 to actuate the indicator 60 to enable the operator to determine the starting position of each tumbler, whereupon each push-pin is again operated to advance each tumbler a sufficient number of steps to bring the channels 37 in the bushings into alignment with the catches 38, 39 and 40 according to the particular 105 combination at which the lock is to be operated which is governed by the relative positions of the ratchet teeth on the annulus to the channels in the bushings. For example, assume the combination to be set at "1" "2" and "3", that is with the tumbler 28 set so that one impulse thereof after the pin 63 actuated by the indicator, would bring the channel 37 in alignment with the catch 38, and the tumblers 29 and 30 set so that two 110 and three impulses of each tumbler respectively after the pin 63, has operated the indicator, the channels 37 would be aligned with the catches 39 and 40. It follows that by operating the push-pins 51, 52 and 53, one, two and three times respectively, after the indicator for each tumbler had designated the starting position, the channels in the tumblers will be aligned with the catches 115 on the slide bar, so that the spring 27 will 120

then operate to advance the slide bar and cause the inclined face 81 to depress lever 80 and positioned tooth 83 in the path of travel of projection 77 on shaft 73 so that on rotation of shaft 73 the projection 83 will be engaged and the latch bolt 65 retracted to an unlocking position. Retraction of the latch bolt 65 acts through lever 85 to restore the slide bar 25 to its retracted position, whereupon if either of the push-pins is operated to turn the tumbler to position the channel 37 therein out of alignment with an adjacent catch, the slide bar will again be locked so as to necessitate re-operation of the tumblers to unlock the lock. If, however, the tumblers are not disturbed after unlocking the lock, the slide bar will return to its advanced position on release of the latch bolt either by releasing the shaft 73 or turning it sufficiently to permit the projection 77 to ride over tooth 83. It will now be seen that if the tumblers are arranged in their unlocking position the latch bolt may be freely operated by turning the shaft 73, thus not necessitating operation of the tumblers each time the latch bolt is to be retracted by operation of the shaft 73.

The lock herein set forth is particularly applicable for use on the doors of dwellings and the like where it is desirable that the door be locked against opening from the outside, yet be locked from the inside; as a provision of the sleeve 69 and its bolt operating means, the latch bolt may be retracted from one side of the lock whether the tumblers are in or out of the locking position. In some instances, however, this feature of the lock may be dispensed with as where it is applied to doors of cabinets or safes, or the like where there is no occasion to unlock the lock from the inside.

I claim:

1. In a permutation lock, a slide bar, a plurality of rotary-tumblers mounted to rotate on said slide bar, a spring for advancing said slide bar, means on said bar engageable with said tumblers for holding said slide bar retracted in opposition to said spring, and means operable on disposing said tumblers in a predetermined position relative to each other whereby said tumbler engaging means is rendered ineffectual to permit advance of the slide bar relative to the tumblers.
2. In a permutation lock, a slide bar, a plurality of rotary-tumblers mounted to rotate on said slide bar, a spring for advancing said slide bar, means on said bar engageable with said tumblers for holding said slide bar retracted in opposition to said spring, and means operable on disposing said tumblers in a predetermined position relative to each other whereby said tumbler engaging means is rendered ineffectual to permit advance of the slide bar relative to the tumblers, a push-pin adjacent each tumbler, and means

whereby movement of the push-pin in one direction will effect a partial revolution of the adjacent tumbler.

3. In a lock, a slide bar, a spring for advancing said bar in one direction, a plurality of rotary tumblers carried by said bar, each being formed with a transverse channel opening to the surface of the slide-bar, a series of catches on said slide-bar, a catch being adapted to engage the side of each tumbler to hold the bar retracted in opposition to said spring, and adapted to enter a channel when aligned therewith, and means for turning each of said tumblers step by step to position the channel therein in alignment with a catch.

4. In a lock, a slide-bar, a spring for advancing said bar in one direction, a plurality of rotary tumblers carried by said bar, each being formed with a transverse channel opening to the surface of the slide-bar, a series of catches on said slide-bar, a catch being adapted to engage the side of each tumbler to hold the bar retracted in opposition to said spring, and adapted to enter a channel when aligned therewith, and means for turning each of said tumblers step by step to position the channel therein in alignment with a catch and permit the bar to advance when the channels are aligned with the catches, a dead bolt, normally inoperative means for retracting said bolt, and means operable by advance of the slide-bar for rendering said last named means operative.

5. In a permutation lock, a plurality of rotary tumblers, means for turning each of said tumblers step by step, lock mechanism operative to unlock on predetermined positioning of said tumblers, means for confining the movement of said tumblers to a forward direction, and means operable by said last named means for indicating a starting position for each tumbler on rotation of the tumbler and means for varying the starting position of each tumbler.

6. In a permutation lock, a plurality of rotary tumblers, means for turning each of said tumblers step by step, lock mechanism operative to unlock on predetermined positioning of said tumblers, a spring pressed detent engageable with each tumbler to hold it against retrograde movement, an indicator operatively connected to said detent, and means on each tumbler arranged to act on said detent to operate said indicator to designate the starting position of each tumbler.

7. In a lock, a rotary tumbler formed with peripheral ratchet teeth, a member engageable with the teeth for holding the tumbler against retrograde movement, an indicator carried by said member, and means on said tumbler for moving said member independent of the ratchet teeth for operating said indicator.

8. In a permutation lock, a rotary tumbler mounted for complete rotation and having ratchet teeth, a spring pressed reciprocal catch engageable with the ratchet teeth to hold the tumbler against retrograde movement, said catch positioned to ride over the ratchet teeth and to be retracted thereby, means for effecting an increased retraction of said catch, and an indicator operable by increased retraction of the catch. 70
9. In a permutation lock, a rotary tumbler adapted to completely rotate and carrying ratchet teeth, a catch engaging said teeth, a projection on said tumbler adapted to effect increased retraction of said catch, and an indicator operable by such increased retraction of the catch to designate a starting position of the tumbler. 80
10. In a permutation lock, a rotary tumbler adapted to completely rotate and carrying ratchet teeth, a catch engaging said teeth, a projection on said tumbler adapted to effect increased retraction of said catch, and an indicator operable by such increased retraction of the catch to designate a starting position of the tumbler, said projection being detachably engageable with the tumbler and adapted to be affixed at various positions thereon. 85
11. In a permutation lock, a slide-bar, a bushing tumbler on said slide-bar and through which the bar may slide said bushing having a channel extending along the bar, a catch on the bar adapted to engage the bushing and to enter the channel, a toothed annulus on said bushing the teeth of which have a relation to the channel in the bushing, and means for detachably holding the annulus against movement on the bushing adapted to be adjusted to vary the relation of a tooth to the channel. 90
12. In a lock, a reciprocal slide-bar, a catch protruding from said bar, a rotary tumbler carried by said bar against the side of which the catch may abut, said tumbler provided with a channel facing the bar through which the catch may pass, means for turning the tumbler step by step to align the channel with the catch, and a movable indicator operated by advance movement of the tumbler to denote the starting point in counting the steps of movement of the tumbler. 100
13. In a lock, a lock casing, a spring pressed normally advanced bolt in said casing, a slide bar in said casing, a spring for advancing said slide bar, a series of rotary tumblers, means controlled by said tumblers for maintaining the slide bar in a retracted position in opposition to the spring, means for retracting the bolt normally out of operative connection therewith, and means operable on advance of said slide bar for operatively connecting the bolt and the bolt reTRACTING means. 110
14. In a lock, a lock casing, a normally advanced spring pressed bolt, means for retracting said bolt normally out of operative connection therewith, embodying a rotary element and a projection on said element; an arm on said bolt having a tooth adapted to be positioned in front of said projection, a spring acting on said arm normally disposing said tooth out of the path of travel of said projection, a slide bar, a spring for advancing said slide bar, a series of rotary tumblers, means co-operating between the slide bar and tumblers for normally maintaining the slide bar in a retracted position, and means whereby advance movement of the slide bar will act on said arm to position the tooth in front of the projection, whereby on rotation of the rotary member the bolt may be retracted. 120
15. In a lock, a lock casing, a normally advanced spring pressed bolt, means for retracting said bolt normally out of operative connection therewith, embodying a rotary element and a projection on said element; an arm on said bolt having a tooth adapted to be positioned in front of said projection, a spring acting on said arm normally disposing said tooth out of the path of travel of said projection, a slide bar, a spring for advancing said slide bar, a series of rotary tumblers, means co-operating between the slide bar and tumblers for normally maintaining the slide bar in a retracted position, means whereby advance movement of the slide bar will act on said arm to position the tooth in front of the projection, whereby on rotation of the rotary member the bolt may be retracted, and means whereby retraction of the bolt will retract the slide bar in opposition to its spring. 130
16. In a lock of the character described, a lock casing comprising side plates having inturned end walls, means for connecting the end walls together, inturned flanges spaced from the end walls, a backing plate adapted to extend over said flanges having threaded openings therein, said backing plate adapted to be secured to the wall of a recess in a door, bolts extending thru the front wall and flange on each side plate screwed into engagement with the back plate, and lock mechanism carried by said plates. 115
17. In a lock, a lock casing, a normally advanced spring pressed bolt, means for retracting said bolt normally out of operative connection therewith, embodying a rotary element and a projection on said element; an arm on said bolt having a tooth adapted to be positioned in front of said projection, a spring acting on said arm normally disposing said tooth out of the path of travel of said projection, a slide bar, a spring for advancing said slide bar, a se- 125

ries of rotary tumblers, means co-operating between the slide bar and tumblers for normally maintaining the slide bar in a retracted position, means whereby advance movement of the slide bar will act on said arm to position the tooth in front of the projection, whereby on rotation of the rotary member the bolt may be retracted, means whereby retraction of the bolt will retract the slide bar in opposition to its spring, and a lever having one end engaged with the bolt and its opposite end projecting into an elongated slot in a slide bar whereby the bar may have movement relative to the lever, said lever adapted to retract the slide bar in op-

position to its spring on retraction of the bolt.

18. In a permutation lock, a plurality of rotary tumblers freely revoluble and unrestricted movement in one direction, means for confining the movement of said tumblers to a forward direction, means for turning each of the tumblers forwardly step by step, lock mechanism operative to unlock on predetermined positioning of said tumblers, and means operable by turning said tumblers forwardly for indicating the starting position of each tumbler independent of the other tumblers.

ELERT A. HILL.
